UNITED STATES PATENT OFFICE

JOSEPH E. GROSS, OF SWISSVALE, PENNSYLVANIA, ASSIGNOR TO AURORA SIGN COMPANY, A CORPORATION OF PENNSYLVANIA

ILLUMINATED SIGN

Application filed April 20, 1929. Serial No. 356,719.

My invention relates to illuminated signs and more particularly to such signs as are provided with letters embodying luminous gas filled tubes.

5 The object of my invention, in general, is to provide an illuminated sign that shall be simple and efficient in operation and capable of being economically manufactured and maintained.

10 A more specific object of my invention is to provide an illuminated sign in which letters embodying luminous gas filled tubes may be disposed in such manner that they may be easily and quickly changed or interchanged to vary the reading thereof.

Another object of my invention is to provide an illuminated sign having changeable letters of luminous gas filled tubes in which all the lines of letters in the sign shall remain substantially equally brilliant regardless of the numbers of letters embodied in each line and any arrangement thereof.

20 It is also an object of my invention to provide an illuminated sign embodying changeable letters of luminous gas filled tubes that shall be especially well insulated from each other and also from the body or frame of the sign.

Other objects of my invention will, in part, 30 be obvious, and will in part, appear hereinafter.

For an illustration of one of the various forms my invention may take, reference may be had to the accompanying drawings in 35 which:

Figure 1 is a view, in front elevation, of an illuminated sign constructed in accordance with my invention;

40 Fig. 2 is a view, in front elevation, partly broken away, of the sign illustrated in Fig. 1 with the letters and the blank letters removed;

Fig. 3 is a view taken along the line III-III of Fig. 1;

45 Fig. 4 is a view, in cross section, of the letter A in the sign, illustrating the manner in which the letter is disposed in the sign;

Fig. 5 is a view, in rear elevation, of the letter A embodied in Fig. 4; and

50 Fig. 6 is a fragmentary view partly in sec-

tion of a sign embodying a modification of my invention.

The drawings illustrate an illuminated sign provided with a casing or frame 1 of a suitable sheet material that is divided into 55 two compartments by a partition wall 2. The corner walls of the casing 1 are welded or otherwise secured together and are provided with stiffening members 3 of angle iron.

50 Mounted on the front of the casing 1 is a suitable face plate 4 that is provided with a plurality of openings 5. All of the openings 5 are of equal dimensions and each one is adapted to receive and hold a luminous sign letter 6 for the purpose of forming an illuminated sign.

70 Each of the sign letters 6 comprises a rarefied gas-conducting illuminating tube 7 that is bent into the form of one of the letters of the alphabet and mounted upon the face of a plate or frame member 8 by means of a plurality of insulating members 9. While any suitable luminous gas-filled tube may be utilized in constructing the letters, I prefer to employ a luminous tube similar to that illustrated and described in my co-pending application, Serial No. 316,707, filed November 2, 1928.

75 The two terminal portions 10 and 11 of the luminous tube 7 are bent at right angles to the body of the letter and extend through a pair of apertures 12 and 13 in the letter frame member 8 into cooperating chambers that are formed by a pair of insulating tubular members 14 and 15 which are secured to the rear face of the frame member. Inasmuch as the tubular members 14 and 15 are constructed of stiff insulating material, they both insulate and protect the terminal portions of the 80 luminous tubes.

85 As shown, the leading-in wires 16 and 17 from the terminal portions of the illuminating tubes extend through holes in the insulating tubes and are connected to a pair of contact members 18 and 19 that are mounted on the free ends of a pair of insulating supports 20 and 21.

90 The insulating supports 20 and 21 are disposed in such a position on the rear face of the letter that, when the letter is placed in the 95 100

sign, the contact members 18 and 19 will engage a pair of cooperating contact members 22 and 23 that are mounted upon a plurality of insulating supports 24 secured to the rear wall of sign casing 1. Inasmuch as the contact members 18 and 19 are mounted in exactly the same position on each of the letters and the cooperating contact members 22 and 23 in the sign casing are disposed in the same corresponding positions with reference to the openings 5, the contact members for each letter will always engage the corresponding cooperating contact members in the sign when the letters are changed or interchanged.

15 In order that the letters 6 may be easily mounted in and dismounted from their positions in the openings 5 when it is desired to change or interchange them for varying the text of the sign, the lower edge of each of the 20 letter frame members 8 is bent upward and then downward to form an inverted U-shaped section 25 that may rest upon the edge 26 of each of the openings 5 in the face plate 4.

The upper edge 27 of each of the letter 25 frame members 8 is adapted to extend into an inverted U-shaped section 28 that is formed at the upper edge of each of the openings 5 in the face plate 4. This construction permits any one of the letters 6 to be easily placed 30 in position by placing the upper edge 27 of the letter in the inverted U-shaped section 28, shoving the letter upwardly until its lower edge clears the lower edge 26 of the face plate and then lowering the letter until the inverted 35 U-shaped section 25 rests astride the edge 26 of the face plate. By reversing this operation, any one of the letters may be easily removed.

If desired a flange 35 may be placed around 40 the tube 7 and welded or otherwise secured to the face of the letter frame 8 to form a channel for the tube.

As a means for supplying high voltage for illuminating the letters in the upper line of 45 the sign, a transformer 29 is disposed in the lower left hand corner of the upper compartment with its secondary connected to the end contact members 22 and 23 by conductors 30 and 31. When the line is completely filled 50 with letters, the contact members 20 and 21 on the letters will engage the cooperating contact members 22 and 23 in the sign casing and thereby complete a series circuit for energizing the gas filled tubes and thereby illuminating 55 the letters. The transformer may receive energy from any suitable source of power represented by the conductors 32 and 33.

As shown, a transformer 34 is similarly disposed 60 in the lower left hand corner of the lower compartment of the sign casing and connected in a similar manner to the contact members for the letters in the lower line.

Inasmuch as the number of letter openings 65 5 in each line are known, the transformers

may be selected to insure an equal illumination of the lines. However, in some cases the words to be embodied in each line may not contain a sufficient number of letters to fill all of the letter openings 5. I have, therefore, 70 provided a plurality of blank letters 36 to be placed in the openings not occupied by letters.

Each of the letter blanks 36 comprises a body member 37 of sheet material of the 75 proper size to fill one of the letter openings 5 and its lower edge is bent into U-shape so that it may be readily disposed in or removed from any one of the openings in a manner similar to that in which the letters are placed 80 in position or removed from the sign. A pair of contact members 38 and 39 are mounted on a pair of insulating members 40 and 41 on the rear face of each blank letter in position to engage the operating contact members 22 and 23 in the sign casing in the same manner as they are engaged by the contact members on the letters. A conductor 42 connects the contact members 38 and 39 on the letter blanks for the purpose of completing the 90 series circuit for the letters when letter blanks are included in the line.

In order that no difference in the illumination of the line may occur when letter blanks 36 are employed to fill in vacant openings, the 95 conductor 42 that connects the contact members 38 and 39 on each of the letter blanks is constructed in the form of a resistor that is approximately equal to the resistance of one of the letters. Therefore, the total resistance embodied in one line of the sign remains 100 practically the same regardless of the number of letters or the number of letter blanks in that line.

In the modified form of my improved sign 105 illustrated in Fig. 6, the contact members 22 and 23 are eliminated and the lamps are connected by a plurality of flexible insulated conductors 43. Each of the conductors 43 is provided on its ends with plug-in contact members 44 and 45 that may be disposed 110 in receiving contact members 46 and 47 on adjacent letters. The length of each of the conductors 43 should be sufficient to permit one end to be plugged into one letter and the other end pulled out of the sign and plugged into the next letter as it is being inserted in the sign.

It will, therefore, be observed that I have 115 provided an illuminated sign in which gas filled tube letters may be employed in such a manner that they can be easily changed and interchanged and in which the lines remain equally illuminated regardless of the number 120 of letters in the words in each line of the sign.

While I have illustrated and described only 125 one form of my invention and one modification thereof, it is obvious that may changes and additional modifications may be made 130

therein without departing from the spirit and scope of the invention.

I claim as my invention:

- 5 An illuminated sign comprising a casing having spaced openings in one side thereof, a plurality of posts of insulating material secured to a wall of said casing, said posts being in line, spaced substantially equal distances apart and extending towards said
- 10 openings, a contact member secured to the outer end of each post, said contact members each having yieldable end portions extending towards adjacent posts, a plurality of plates disposed in said openings, means on said
- 15 plates and casing for locking the plates in position in said casing openings, luminous tubes secured to some of said plates, two posts of insulating material secured in line to each plate, contact members on said posts, conductors connecting the terminals of the respective tubes to the contact members on the posts carried by the plates to which the tubes are secured, said plates when in position in the casing openings causing positive pressure engagement with adjacent ends of two contact members carried by the posts secured to said casing wall, said tubes when the plates are mounted in place, being connected in circuit relation by said contact members, and
- 20 25 30 means for connecting said tubes to a source of alternating current.

In testimony whereof, I have hereunto subscribed my name this 23rd day of February, 1929.

35
